(57) **CLAIM**

The ornamental design for the desk, as shown and described.

DESCRIPTION

FIG. 1 is a front elevational view of a desk showing my new design;

FIG. 2 is a rear elevational view thereof;

FIG. 3 is a top plan view thereof;

FIG. 4 is a right side elevational view thereof, the left side being a mirror image thereof; and,

FIG. 5 is a front left side perspective view thereof.

Portions of the drawings shown in broken lines are for illustrative purposes only and form no part of the claimed design.
